UNITED STATES PATENT OFFICE.

CHARLES J. VAN DEPOELE, OF CHICAGO, ILLINOIS.

ELECTRIC-ARC LAMP.

SPECIFICATION forming part of Letters Patent No. 291,653, dated January 8, 1884.

Application filed October 19, 1883. (No model.)

To all whom it may concern:

Be it known that I, CHARLES J. VAN DEPOELE, a citizen of the United States of America, residing at Chicago, in the county of Cook and State of Illinois, have invented certain new and useful Improvements in Electric-Arc Lamps, of which the following is a specification, reference being had therein to the accompanying drawings.

10 My invention relates to that class of electric lamps which are usually styled "arc-lamps;" and it consists in certain novel details of construction and arrangement, as will be fully hereinafter described.

15 In the accompanying drawings, which form a part of this specification, Figure 1 is an elevation of my lamp with the front of the inclosing top case removed to show the working parts. Fig. 2 is an inverted plan view, showing the relative positions of the working parts. Fig. 3 is a detached plan view of the lifter. Fig. 4 is a diagrammatic view of the vibrating device, and it also shows the connections between the main and shunt magnets and the 25 relative positions of the several parts.

Similar letters denote like parts.

In the drawings, A is the lower, B the upper, carbon; C, the lower-carbon holder; D, the lower metallic frame, E the upper one, forming or supporting an inclosing-case around the feeding devices placed therein, and although both frames form rigid construction mechanically, they are electrically disconnected in the usual way at *a a* or other suitable points. Inclosed in the upper case, and placed in symmetrical positions in relation to the upper carbons, are the two electro-magnets F and G, provided with the armature H, which is hinged at *b* and connected with the other end at *c* by 35 a link, I, to the lifter J. This lifter J is hinged to the support *d*, and its construction is as follows: It consists of two like halves joined on the under side by an elastic plate or strap, *e*, riveted or otherwise secured thereto. Each 40 of the inner ends of the two parts has a half circular enlargement, forming with the elastic plate a circular clamp adapted to hold or release the upper carbon, in the manner herein-after described.

45 K K' are adjusting-screws stopping the downward movement of the lifter. When not in

operation, J being hinged at *d*, one half of it will naturally drop down on adjusting-screw K, and the other half will drop down on adjusting-screw K', which stands somewhat lower than K, and in this position, the jaw being 55 opened, allows the upper carbon to drop down upon the lower carbon; but as soon as the lifter J is raised from its resting position the jaws close with the upper edge upon the carbon and 60 hold it fast, carrying it upward with it.

L is a coil of fine wire, wound upon the core M and mounted upon the insulated base O.

R and R' are two vibrating armatures, regulated by set-screws *f* and *f'* passing through 65 posts *g* and *g'*.

Electrical connections are established as follows: P and N are the two posts to which the wires from the battery or dynamo-machines are connected. The current, entering at P, 70 passes through the upper frame to the top or positive carbon, then down said carbon to the lower one, hence to lower frame. From there it is carried by a proper electrical connection to a point marked 6, where it enters through the 75 upper frame and is carried to the electro-magnet F, comes out of said magnet on the inner side, and passes over to magnet G, and from there to the negative pole N, and thereby completes the circuit. It will be seen that 80 the first or starting circuit of the lamp is from the frame E to the upper carbon, to the lower carbon, to the frame B, through the connections at 6, to both of the magnets F and G, and out through the negative pole N. The 85 further connections are made as follows: From 1 extends a conductor, which passes to a piece of the magnet-frame at 2, which is in metallic contact with the magnet-core M. From the core M, at the point 4, the current passes (when the 90 circuit is completed) to the vibrating armature R' at the point 3, thence through wire 5, which connects with the main conductor at a point in advance of the main or carbon-controlling magnets F and G. The vibrating and 95 fixed points 3 and 4 never make permanent contact, and this by-pass circuit through them, being of low resistance, causes the current flowing through the said main magnets to pulsate in accordance with the interruptions 100 between the points 3 and 4, the main magnet being short-circuited every time the vibrating

armature and core M come together. The shunt-magnet L, of high resistance, is energized by a current that is caused to pulsate or be interrupted as hereinafter described, and the 5 said current is established between the two poles of the lamp as follows: The inner wire of the coil L of said magnet is electrically connected to the frame at or near the positive binding-post at 7. Thence it passes to said coil 10 at 8, out at 9, thence to vibrating circuit-interrupting armature R at 10, thence through adjustable contact-screw f to post g at 11, and is brought to the main circuit at 12, whence it passes to the negative binding-post N. The 15 vibrations of the armature R alternately make and break the above-described circuit, from which it will be seen that the instant both the said armatures R R' touch the core M the main magnets are short-circuited and almost 20 entirely demagnetized, releasing the upper-carbon-holding devices, while at the next instant the shunt-circuit is interrupted, the energy of the main magnets restored, and the descent of the carbon stopped. By the use 25 of the adjusting-screws f f', these interruptions may be made to occur simultaneously, or with greater frequency, in either one or the other of the aforesaid circuits, so that the upper carbon will descend with a shaking motion, 30 which, to secure steadiness in the light, must be practically continuous.

Having described the different parts of my lamp and the various electric connections, I now proceed to explain its operation.

35 As soon as electric connections with the source is established the magnetic cores F and G lift up the armature H and at the same time the lifter J, which has to partake in all its movements, and the latter, clamping the upper carbon, raises the same from its contact with the lower one, and thus establishes the arc; but soon the carbons will wear away, so that it is necessary to feed the same down as fast as consumed, and this has to be done as 40 nicely as possible in order to produce a steady light. Now my device begins to operate as follows: The vibrating system, being electrically connected, will vibrate quietly and evenly at first—that is, as long as the carbons are 45 at their proper distance apart; but as the distance increases the increased amount of current shunted through the fine-wire coil L causes the vibrations to become more energetic, and now it is that the second vibrating 50 armature, R', comes into action. This armature R' will vibrate isochronously with the one marked R, until its vibrations are energetic enough to make it (the vibrating armature R') strike the core M. This contact allows the 55 current to be diverted from the magnets F G

through the conductors 5 3 4 M 2 1, instead of through the said magnets. The current through F G thus becomes pulsatory, and when pulsations are well defined the armature H will vibrate isochronously therewith, and, by its connections with the lifter, allow the top carbon to feed down gradually. When the proper distance of the carbons is obtained, the vibrating armatures lose power, and R' ceases to act until the carbons again need feeding. The 70 proper working of the vibrating armatures R R' may be obtained by using a stiffer spring to support them, by placing them a greater distance from the core, or in any other desired manner.

I make no claim in this case to the lifter J, made in two parts, which are united by a spring-connection, as that forms part of the subject-matter of another application, filed December 15, 1881, Serial No. 47,963, of which 80 this is a division, nor to an electric-arc lamp having a movable carbon-carrier, a feed regulating and adjusting device for the same, and means adapted to produce a vibratory motion upon the feed mechanism for causing it to feed 85 the movable carbon, which also forms part of the subject-matter of the same application.

What I claim as new is—

1. In an electric-arc lamp, the electro-magnets F G, located in the main circuit, and provided with an armature, H, hinged at one end to one of the poles of said electro-magnet, the free end thereof coming in close proximity to the other pole, where it is free to move in a radius prescribed by the center of its articulation 90 to the opposite pole of the said electro-magnet, in combination with the clamping mechanism carried and operated by said hinged armature, substantially as described.

2. In an electric-arc lamp, the combination 100 of the magnets F G, located in the main circuit, the armature H, lifter J, and suitable carbon-holder, with the coil L, of relatively-high resistance, located in a shunt around said main magnets, the vibrating armatures R R', and adjusting devices and connections, substantially as described, between said main and shunt circuits, as set forth.

3. In an electric-arc lamp, the flexible lifter J, in combination with adjusting-screws K K', adapted to be set at different heights, and thereby to forcibly open the descending clutch, substantially as set forth.

In testimony whereof I affix my signature, in presence of two witnesses, this 5th day of October, 1883.

CHARLES J. VAN DEPOELE.
